BOOKMARK AND BOOKHOLDING DEVICE

Harry A. Jaffin, Astoria, N. Y.

Application January 16, 1948, Serial No. 2,755

2 Claims. (Cl. 281—42)

1

This invention relates to a page holding device for books, and more particularly to a combination page prop or marker for books, and still more particularly my invention relates to a combination book marker and book compactor.

My invention, in one embodiment thereof, has utility with regard to bulky books, the pages whereof are of such size and so bound into a stack which will not readily remain open to any particular page so that reference thereto without the use of the hands manually to retain the book opened to the desired page is not readily possible. Particular reference is made to binders or files for the storage of inactive prescriptions used by pharmacists. In files or binders in this field, the holding of the file open to a predetermined prescription or page, while leaving the hands free for compounding the prescription, is impossible and it is accordingly an object of my invention, in one embodiment thereof, to provide a page holding device for a book comprising a prescription file which may be readily applied in position quickly, to hold the prescription file or book open for inspection of a predetermined page.

Still more particularly, it is an object of my invention to provide a page holding device for a book, such as a prescription file, in which the binding thereof cooperates with a prop whereby the page prop is held in position and coordinate-ly combines to balance a divided stack in the propped position for ready inspection of the page, freeing the hands.

Still further objects of my invention reside in the provision of a combined file and page holding device wherein simply shaped wire coordinate-ly combines the parts thereof to compact and hold a file or book closed, or may be converted to a page prop, to hold the bound pages open to any predetermined leaf, to simplify reading of this page without the use of the hands.

Still further, it is an object of my invention to provide a page holding device for loose leaf books or like files in which the binding means for the pages cooperate with a resilient member carrying a prop to hold the prop in position, without injury to the pages, while effectively dividing the stack of pages for ready inspection.

Still further, it is an object of my invention to provide a page holding device for books, files, binders, which may be made inexpensively, while effectively serving its intended purpose.

To attain these objects and such further objects as may appear herein, or be hereinafter pointed out, I make reference to the accompany-

2

ing drawing forming a part hereof, in which— Figure 1 is a perspective view illustrating my invention in the form of a prescription file;

Figure 2 is a perspective view of the same in the open position;

Figure 3 is a perspective view illustrating the application of the page holding device;

Figure 4 is a perspective view of another embodiment of my invention.

Making reference to the drawing, for purposes of illustration, I have shown a form of prescription file 10, having cover members 11 and 12, hinged to a panel 13 along the usual hinge lines 14 and 15. The panel 13 on its inner surface 16 supports binding means 17.

In the illustration, the binding means comprises end plates 17 and 18 which removably support posts 19, 19 for holding the stack 20 of prescriptions in looseleaf fashion. The construction just described will be recognized as a familiar form of prescription file employed by druggists to store inactive prescriptions numerically, to be available for renewal or refilling.

In accordance with my invention, I provide a page holding device 21 which is drawn from spring wire and comprises branches 22 and 23, joined by the coil 24 resiliently to urge the arms with relation to each other outwardly. The arms 22, 23 terminate at their ends 25 and 26 with hooked fingers 27 and 28, respectively. The arms 22 and 23 are guided in a single plane transverse to the axis of the loop 24. Along the length of the arms 22 and 23 and in a plane substantially in parallelism to the axis through the coil 24, I provide props 29 and 30, made by folding the wire of which the branches are made to provide loops 31 and 32, outlining the propping ends between the connecting arm 33.

With a prop of the character described, the stack 20 may be divided at any page which it is desired to inspect, as for refilling a prescription, in the case of a prescription file, thus providing an overlying stack portion 20a. In this position, the fingers are released resiliently to urge the branches 22 and 23 into post engaging position and to direct the opposed propping folds 31 and 32 between the lower stack and the upper stack 20a, as more clearly illustrated in Figure 3. In this position, prop arms 29 and 30 do not obscure the page, to hold the upper stack 20a braced to permit ready inspection of the page, and release the hands for manipulative operations, such as compounding a prescription.

While the page holding device described by me has utility as an individual element which

may be associated with any binding means, I may, in a more particular embodiment of my invention, employ the same as in permanent association with the file or book, more compactly to draw the covers 11 and 12 toward each other and restrain the bulking action of the stack of prescriptions. For this purpose, I provide eyelets 34 and 35, attached to the cover 12 by riveting or other suitable means. The eyelets are spaced apart from each other within the limits of distension of the arms 22 and 23 so that by pinching the arms toward each other, the hooks 27 and 28 may be guided into the eyelets 34 and 35, to hold the prop 21 assembled with the cover 12. The cover 11, in a complementary position to the eyelets, is provided with a hook 36, riveted thereto. The branches 22 and 23 are of a length substantially equidistant to the panel 13, whereby, upon folding the covers 11 and 12 toward each other as shown in Figure 1, the coil 24 may be hooked onto the hook 36 to hold the covers 11 and 12 in parallelism. In this position, a stack of pages, such as prescriptions, of great thickness may be bound compactly.

It will be observed that while in the exemplified form of my invention I may provide a prop having prop supporting arms closely positioned to each other so that they may be grasped by the fingers of one hand, it will be understood that where the binding means may involve posts widely spaced from each other, I may apply the principle of my invention to larger books or files in which the binding means is spaced at greater distances.

In Figure 4 I have illustrated a prop 21a in which prop arms 22a and 23a are formed substantially identically with the prior embodiment and are joined to the spacer section 37 by a pair of coils 38 and 39. The spacer section 37 is of a length to space the coils 38 and 39 approximately equivalent to the space between the posts 40, 40, which may be of more extended size, such as a two ring binder ledger or other bookkeeping device, the hook fingers 41 and 42 being of a length commensurate with the thickness of the posts 40, 40 to prevent displacement.

It is understood that normally the arms 22a and 23a are distended resiliently in a direction from each other, in which case the fingers 41 and 42 may point away from each other, so that the arms 22a and 23a must be drawn toward each other to hook the fingers 41 and 42 between the pages of the stack and the posts 40, 40, as in the prior embodiment.

The divided stack maintains the prop between the same whereas the resilient action of the hooked fingers with relation to each other against the post or binding means holds the props from being pinched outwardly.

It will be understood that while in the preferred embodiment, the arms 22, 23, and 22a, 23a are normally resiliently urged away from each other, I may, by an inversion of the hooked fingers 27,

28 and 41, 42 engage other portions of the binding means and likewise resiliently urge the arms so that they normally are in close proximity to each other and would require movement from each other against the normal resilient pressure of these arms so as to engage the binding means by releasing the arms to move toward each other.

While I have shown and described the arms resiliently urged relatively to each other by the employment of drawn spring wire, it will be understood that flat spring steel may be employed and that merely a change in size is required to adapt the prop to take care of the weight and dimensions of the hook or file with which the prop is to be used.

It will thus be observed that I have provided a novel and inexpensive page holding device or book prop, which combines with the covers thereof to provide a book holding device which compacts the bulk of the pages of the stack, as well as to amplify the use thereof for the purposes described.

Having thus described my invention and illustrated its use, which I claim as new and desire to secure by Letters Patent, is:

1. A page holding device for a book having binding means for the pages thereof, comprising wire drawn to provide spaced arms resiliently joined by a loop at one end of the arms forming the flexing portion for moving the arms to and from each other, hook fingers in a plane common to the plane in which the arms lie, said hook fingers being directed in opposed relation to each other on said arms, and drop members along the arms transversely extended to the plane in which the hook fingers are directed.

2. A page holding device for a book having binding means for the pages thereof, comprising a pair of wire spaced arms resiliently joined at one end of the arms forming the flexing portion for moving the arms to and from each other, hook fingers in a plane common to the plane in which the arms lie, said hook fingers being directed in opposed relation to each other on said arms, and prop members along the arms transversely extended to the plane in which the hook fingers are directed.

HARRY A. JAFFIN.

Certificate of Correction

Patent No. 2,565,966

August 28, 1951

HARRY A. JAFFIN

It is hereby certified that error appears in the printed specification of the above numbered patent requiring correction as follows:

Column 4, line 34, for "drop" read *prop*;
and that the said Letters Patent should be read as corrected above, so that the same may conform to the record of the case in the Patent Office.

Signed and sealed this 19th day of February, A. D. 1952.
